THERAPEUTIC BAG

Louis B. Newman, Chicago, Ill.

Application July 6, 1937, Serial No. 152,006

6 Claims. (Cl. 128—400)

This application is a continuation in part of my pending application, Serial No. 98,437, filed August 29, 1936.

This invention relates to therapeutic devices, and more particularly, to such apparatus as is used for the application of heat or cold to internal or external parts of the human body, as for improving the circulation or aiding in the resolution of abscesses, or other abnormal conditions, for the destruction of pathogenic micro-organisms and for improving the distribution and action of medicaments that are applied to the surface of the human body, either internally or externally.

Certain micro-organisms which are pathogenic can be destroyed by the application of heat at a temperature somewhat below the temperature which is destructive of human tissue. In one form of therapeutic treatment a highly elastic thin bag is inserted into a body cavity, such as the vagina, and is inflated by circulating hot water therethrough, the intention being to maintain the temperature of the water below that which will cause destruction of the surrounding tissue and above that at which certain infecting micro-organisms can live, with the result that the infection is cleared up. In my prior application, Serial No. 98,437, to which reference may be had, I disclose such apparatus wherein the heated fluid that is being circulated is air, instead of water. The present invention relates to the construction of the applicator that is inserted into or placed against the body and through which the heated air or water is being circulated. The applicator must necessarily comprise an elastic bag which is very thin or membranous whereby upon inflation it assumes the shape of the cavity within which it is inserted so that it contacts all of the surface of the cavity to be treated. If the bag should fail to contact certain parts of the surrounding surface those parts might not receive the beneficial therapeutic treatment with the result that foci of infection might remain after completion of the treatment, thus nullifying the entire effect of the treatment. In order to accomplish this result the bag of the applicator must be exceedingly thin. This means that there is considerable possibility of bursting of the bag. If this occurs the physician must be able to quickly remedy the defect. I accomplish the above result by providing an applicator head comprising preferably a stiff rubber tube, to which applicator head the thin rubber bag is applied by merely slipping the same over the open end of the applicator head. In order to seal against leakage of the heating medium, whether the same be air or water, I provide an additional tube of rubber which slips over the open end of the applicator bag and provides a double seal against outward leakage. By clip-

ping the second tube back I expose the end of the applicator bag and thus provide for the ready removal of a torn applicator bag and replacement by a good bag.

In therapeutic treatment of the above character it is desirable that the temperature be maintained as high as possible consistent with non-injury to the human tissue. As a result it becomes necessary for the physician to operate at a temperature very close to the dangerous temperature and it is therefore necessary that the physician know exactly what is the temperature within the applicator bag. In the prior constructions with which I am familiar the temperature of the circulating water was read at some point remote from the bag and was frequently erroneous, resulting in many instances either in an excessive temperature being reached, causing burning of the tissue, or the temperature maintained was too low, whereby the desired beneficial effects from the therapeutic treatment were not obtained. It is an object of the present invention to overcome both of the above mentioned difficulties. I accomplish this result by placing a thermometer in the applicator head, with the bulb of the thermometer within the applicator itself, so that the thermometer reads directly the temperature within the applicator bag. By this arrangement the physician knows at all times what is the actual temperature within the applicator and therefore knows if the temperature is high enough to effect the desired results and if the temperature is approaching the danger point where burning might result.

The attainment of the above and further objects of the present invention will be apparent from the following specification taken in conjunction with the accompanying drawing forming a part thereof.

In the drawing:

Figure 1 is a diagrammatic view illustrating one embodiment of therapeutic apparatus to which my applicator may be applied;

Figure 2 is an enlarged sectional view through a portion of the applicator of Figure 1, said view illustrating the manner whereby the applicator bag is applied to the applicator head;

Figure 3 is a view corresponding to Figure 2 and showing the applicator bag on the applicator and ready for use;

Figure 4 is a sectional view taken along the line 4—4 of Figure 3; and

Figure 5 is a sectional view taken along the line 5—5 of Figure 3.

Reference may now be had more particularly to Figure 1 wherein I illustrate a therapeutic apparatus of the type shown in my application above referred to, which is one type of apparatus to which the present invention is applicable. The applicator is indicated at 1 and comprises a thin

rubber bag of a proper shape, depending upon the particular body cavity for which the applicator is intended. The bag is of thin rubber so that upon inflation it expands to fill the body cavity in which it is placed and contacts as large a portion of the surface of the cavity or external area as is desirable. The applicator illustrated at 1 is of a shape particularly adapted for treatment of the vagina. The applicator head is indicated at 2, the applicator being secured to the lower end of the applicator head. A thermometer 3 extends through a suitable opening in the applicator head and its thermo-responsive part extends into the applicator proper, so that the thermometer indicates the actual temperature within the applicator. The applicator 1 is provided with an air inlet opening adapted to receive a pipe or tube 4, and an air outlet opening adapted to receive a pipe or tube 5.

20 The tubes 4 and 5 extend to the control apparatus located at a convenient adjacent place and which includes a tempering casing 7 for heating or cooling the air, and a fan 8 in a housing, connected together and to the pipes 4 and 5 so as to constitute a closed air circulating system. Air is moved by the fan 8 through the casing 7, thence through the tube or pipe 4, through the applicator 1, outlet pipe 5 and back to the inlet of the fan. The pressure within this circulating system is determined by the quantity of air in the system. The system is made leak-proof to guard against escape of air and consequent loss of pressure. Means is provided for increasing or decreasing the amount of air in the system so that any desired pressure is obtained. This means comprises a bulb pump 10 connected by a tube 11 to the air circulating system at any desired point, for instance at the casing 7. The bulb pump 10 comprises a rubber bulb and a suitable valve arrangement so that upon compression of the bulb the air therein is forced through the tube 11, whereas upon release of the pressure on the bulb 10, air is drawn into the bulb from the atmosphere through an inlet 12, instead of through the tube 11. The inlet 12 may also be operated manually to permit escape of air from the system. This is the usual type of bulb pump used with the ordinary portable blood pressure determining device. A pressure gauge 14 is provided for determining the pressure in the system.

An electric motor 15 is provided for operating the fan 8, and a coil 16, hereinafter referred to as a tempering coil, is provided for heating or cooling the air in the circulating system. In the case of an apparatus designed for cold treatment, the tempering coil 16 may comprise a coil connected to receive a refrigerant from a refrigerating system. In the case of a heat treating apparatus, the coil 16 comprises an electrical resistance coil. The desired temperature for which automatic regulation is maintained can be changed by operating a knob 17 of an automatic thermostatic control 18. In the case of an electric system the knob 17 adjusts a resistance in the control apparatus 18 to alter the value of the temperature maintained constant by the control apparatus.

The applicator head consists of an outer pipe 20, preferably of rather thick rubber to give it the requisite stiffness, and preferably oval in cross section. The pipe 20 has a thickened portion 21 extending longitudinally thereof at its lower end, which thickened portion has a bore 22 for receiving the thermometer 3. The ther-

momter seals in the bore 22 so that there can be no escape of air from the applicator through the bore 22 at the point of entrance of the thermometer. The pipe 20 is adapted to be connected with a short pipe 24 by means of a severable sealing coupling 25 suitably gasketed and secured to prevent the leakage of air. The pipe 24 has two branches, namely a branch 28 and a branch 29. The branch 28 is adapted to receive the rubber tube 5 at its outer end and constitutes the air outlet side of the applicator. The branch 29 has a pipe 30 therein which extends through that branch and through the pipe 20 to the applicator bag. The applicator bag 1 is formed, preferably, of pure rubber having great strength and elasticity and constitutes a very thin membrane. The pipe 20 has a length of thin rubber tubing 35 slipped over the lower end thereof and secured in place in any desired manner, as by vulcanizing the same to the pipe 20 around the periphery 36, or cementing it thereto around the periphery 36. This vulcanization or cementing is only along the end of the tubing 35, and all around the periphery thereof, so that the lower end of the tubing 35 is unsecured to the adjacent portion of the pipe 20. It is therefore possible to roll the lower end of the tubing 35 upon itself upwardly on the pipe 20 to the position shown in Figure 2. For the purpose of facilitating illustration I have shown this tubing in its rolled form of appreciably greater thickness than its actual thickness. That end of the applicator bag 1 which is to be secured to the tube 20 is tubular in section so that it may be rolled upon itself in the manner illustrated in Figure 2, and the rolled part thereof then slipped over the end of the pipe 20, as indicated at 39 in Figure 2. The roll 39 of Figure 2 has also been shown as appreciably thicker than the actual thickness thereof, in order to facilitate illustration, since the rubber of the applicator 1 is exceedingly thin. After the applicator has been placed in the position illustrated in Figure 2 the roll 39 is rolled upwardly so that the tubular portion of the applicator tightly embraces the lower end of the applicator head or pipe 20. Thereafter the roll 39 of the tubular section 35 is rolled downwardly over the top portion of the tubular extension 40 of the applicator, whereby the parts assume the position illustrated in Figure 3.

It is apparent from the construction illustrated in Figure 3 that any air leaking out of the applicator bag 1 must travel between the tubular section 40 and the outer surface of the pipe 20 until it passes over the top of the tubular section 40, and then must travel down between the tubular section 40 and the inner surface of the tube 35, whereby a double seal is obtained. Furthermore, the tubular section 40 tightly embraces the tube 20, and the tube 35 tightly embraces the section 40, thereby further facilitating the sealing action. Any fluid that might pass between the tubular section 40 and the outer lower surface of the tube 20 will cause a slight increase in the effective diameter of the tubular portion 40 and thereby press that tubular section into firmer contact with the rubber of the tube 35. Thus any weakening of the innermost seal, to wit: the seal between the section 40 and the pipe 20, must necessarily result in a tightening of the outer seal, to wit: the seal between the section 40 and the section 35.

The applicator 1 may readily be removed from the tube 20 by merely rolling the tube 35 upwardly back to the position illustrated in Figure 2.

2, and then rolling the tubular section 40 down to the position illustrated in Figure 2. This facilitates removal of the applicator bag 1 for replacement purposes or for removal of the thermometer 3, which may become necessary in the event of breakage of the thermometer.

While I have here illustrated my invention as applied to a therapeutic device constructed in the manner shown in my prior application for Letters Patent, wherein the circulating medium is air, it is to be understood that this invention is equally applicable to therapeutic apparatus for like purposes wherein the circulating medium is water, which latter apparatus is well known at the present time, or wherein a cooling instead of a heating fluid is circulated.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

25 1. A therapeutic device comprising an applicator head having a tube, an applicator bag having a neck detachably and intimately embracing the entire outer circumference of said tube throughout a substantial distance lengthwise of said tube, and a resilient sheath having a permanent leak-proof connection around said tube and detachably embracing the tube-embracing portion of said neck and exerting a pressure thereagainst.

35 2. A therapeutic device comprising an applicator head including a tube and a relatively elastic sheath about and having a leak-proof fixed connection with said tube at the end of the sheath that is farthest from the end of the head and separable from the tube at the opposite end of the sheath, and an elastic membranous applicator bag having a neck detachably elastically and intimately fitted about said tube and within the unconnected part of said sheath, said sheath engaging and exerting a pressure on said applicator bag.

50 3. A therapeutic device comprising an applicator head including a tube and a relatively elastic sheath tensioned around said tube and having a leak-proof fixed connection with said tube around the periphery of the sheath at the end of the sheath that is farthest from the end of the head, and an elastic membranous applicator bag having a neck detachably elastically and intimately fitted about said tube and within the unconnected part of said sheath and engaging said tube substantially to the juncture of said tube and sheath and pressed towards said tube by said sheath.

55 4. A therapeutic device comprising an applicator head including a tube and a membranous relatively elastic sheath joined to said tube and extending free of said tube beyond its juncture with said tube, said juncture being leak-proof, and an elastic membranous applicator bag having a neck formed to be rolled upon itself and to be expanded to fit over an end of said tube and then unrolled to elastically clasp said tube and remaining mechanically separate from said tube to permit it to be subsequently rolled upon itself for removal of said neck from said tube,

the free portion of said sheath being formed to be rolled upon itself to enable said neck to be moved onto said tube, said sheath being formed to be unrolled thereafter to elastically clasp and sheath said neck.

5 5. A therapeutic device comprising a tubular applicator head, a membranous tubular rubber sheath sprung about and embracing said head from adjacent an end of the head to a point on the head substantially spaced from said end and secured to said head at said point by a leak-proof seal encircling the head, said sheath and head being disconnected from said point of sealing connection to the end of the sheath so that the sheath may be rolled upon itself within its elastic limits to expose the end of the head and unrolled to lie along the head, an elastic membranous applicator bag having a tubular neck which can be sprung within its elastic limit about the end of the applicator when the sheath has been rolled from the end of the head to expose the same, and to intimately and firmly embrace the head and form a leak-proof detachable connection between the bag and the applicator head, said sheath being formed to permit complete unrolling of the same to overlie and tightly embrace the neck of the bag and form a sealing detachable fit over the outside of the neck of the bag, said sheath being mechanically separate from said bag to permit the end of the sheath which overlies the end of the head to be rolled back upon itself and expose the neck of the applicator bag to permit removal and replacement of the applicator bag.

35 6. A therapeutic device comprising a tubular applicator head, a membranous tubular rubber sheath sprung about and embracing said head from adjacent an end of the head to a point on the head substantially spaced from said end and secured to said head at said point by a leak-proof seal encircling the head, said sheath and head being disconnected from said point of sealing connection to the end of the sheath so that the sheath may be rolled upon itself within its elastic limits to expose the end of the head and unrolled to lie along the head, an elastic membranous applicator bag having a tubular neck which can be sprung within its elastic limit about the end of the applicator when the sheath has been rolled from the end of the head to expose the same, and to intimately and firmly embrace the head and form a leak-proof detachable connection between the bag and the applicator head, said sheath being formed to permit complete unrolling of the same to overlie and tightly embrace the neck of the bag and form a sealing detachable fit over the outside of the neck of the bag, said sheath being mechanically separate from said bag to permit the end of the sheath which overlies the end of the head to be rolled back upon itself and expose the neck of the applicator bag to permit removal and replacement of the applicator bag.
